UNITED STATES PATENT OFFICE

2,110,633

RAILROAD FROG

Michael Pikarchuk and Lina Pikarchuk, Nicholson, Ontario, Canada

Application December 20, 1935, Serial No. 55,479

1 Claim. (Cl. 246—276)

This invention relates to certain new and useful improvements in railroad frogs.

The primary object of the invention is to provide a railroad frog wherein a tensioned wing rail is associated with the point of the frog and adapted for automatic shifting movement when engaged by the wheel or flange of a wheel of rolling stock, the cooperating wing rail being anchored to the base plate.

10 A further object of the invention is to provide a railroad frog of the foregoing character embodying a particular type of tensioning means for an automatically shiftable wing rail and means for guiding the wing rail during its movement.

15 With the above and other objects in view that will become apparent as the nature of the invention is better understood, the same consists in the novel form, combination and arrangement 20 of parts hereinafter more fully described, shown in the accompanying drawing and claimed.

In the drawing:—

Figure 1 is a top plan view of a railroad frog constructed in accordance with the present invention, showing the guide means for the tensioned automatically shiftable wing rails;

Figure 2 is a side elevational view;

Figure 3 is an end elevational view looking in the direction of the point rails;

30 Figure 4 is an opposite end elevational view looking in the direction of the wing rails; and

Figure 5 is a cross-sectional view taken on line 5—5 of Figure 1, showing the tensioning means for the automatically shiftable wing rail associated with both the shiftable and stationary wing rails.

Referring more in detail to the accompanying drawing, the railroad frog comprises a base plate 10 having openings 11 adjacent opposite side edges for the passage of spikes for anchoring the frog to rail ties. The side of the base plate 10 with which the movable wing rail of the frog is associated is provided with a slotted opening 12 providing snow clearance for easier operation and movement of the wing rail.

One end of the base plate 10 has the point rail sections 13 anchored thereto that merge into the frog point 14. A pair of wing rails 15 and 16 is operatively arranged at opposite sides of the point 14, the wing rail 15 being anchored to the base plate 10 by integral formation therewith as illustrated in Figure 5, while the wing rail 16 is automatically shiftable over the base plate relative to the point 14. As shown in Figure 1, the slotted openings 12 extend trans-

versely into the base plate 10 a sufficient distance to underlie the movable wing rail 16 and with the openings positioned between the supporting ties, the movable wing rail acting to clean and scrape the snow from the base plate and direct the snow through the slotted openings. The tensioning means for normally retaining the automatically shiftable wing rail 16 in position adjacent the point 14 is shown more clearly in Figure 5 and includes a rod 17 transversely slidable through the wing rails 15 and 16. A cup member 18 is mounted on each end of the rod 17 with the latter slidable therein, the bottom wall 19 of the cup member 18 being engaged with the outer face of the adjacent wing rail. 15 A coil spring 20 surrounds each end of the rod 17 within the cup member 18 and is tensioned by means of the plug 21 engaged with the outer end thereof and adjusted on the threaded end of the rod 17 by means of the nut 22. The spring members 20 at the outer sides of the wing rails 15 and 16 cooperate with said wing rails for tensioning the wing rail 16, the springs centering the rod 17 and automatically moving the wing rail 16 toward the frog point 14.

The wing rail 16 is guided in its movement by means of pins 23 projecting outwardly thereof and extending through guide straps 24, the buffer or stop 25 rising from the base plate 10 cooperating with the guide straps 24 for limiting movement of the wing rail 16 away from the frog point 14.

From the above detailed description of the invention, it is believed that the construction and operation thereof will at once be apparent, it being noted that the wing rail 16 is doubly tensioned by the spring devices 20 associated with the outer sides of the wing rails 15 and 16. Tension springs 20 are housed within the cup members 18 for protective purposes. The blocks 21 function to exclude snow or other foreign matter from the cup members 18 for the protection of the spring members 20.

While there is herein shown and described the preferred embodiment of the invention, it is nevertheless to be understood, that minor changes may be made therein without departing from the spirit and scope of the invention as claimed.

We claim:—

In a railroad frog, a base plate, point rails on the base plate leading to a point, a wing rail on the base plate at each side of the point, one of the wing rails being stationary and integral with the base plate between the side edges thereof, 55

the other wing rail being slidable on the base plate and movable towards and away from the point, the side of the base plate beneath the movable wing rail being provided with snow clearing transversely extending slotted openings with the openings extending inwardly from the edge of the base plate to points beneath the movable wing rail, guide members on the base plate outwardly of the movable wing rail, guide pins on the movable wing rail extending into the guide members, a buffer stop on the base plate intermediate the guide members adapted to limit outward movement of the movable wing rail, a rod transversely slidable through the wing rails, a

cylindrical cup member on each projecting end of the rod having a bottom wall engaged with the adjacent wing rail, a spring surrounding each end of the rod within the cup member, a block on each end of the rod of slightly smaller diameter than the cup member extending into the open outer ends of the cup members for tensioning the springs for normally retaining the movable wing rail in engagement with the point and for substantially closing the outer ends of the cup members to prevent entrance of snow or the like therein. 5 10
